CLAIM

The ornamental design for a fastening angle, as shown and described.

DESCRIPTION

FIG. 1 is a perspective view of a fastening angle showing our new design, which is a mirror image of the opposite side thereof;

FIG. 2 is a side view thereof;

FIG. 3 is a front view thereof;

FIG. 4 is a top plan view thereof;

FIG. 5 is an opposite side view thereof;

FIG. 6 is a rear view thereof; and,

FIG. 7 is a bottom plan view thereof.
